UNITED STATES PATENT OFFICE.

JOHN KNOUS, OF HARTFORD, CONNECTICUT, ASSIGNOR TO THE POPE
MANUFACTURING COMPANY, OF PORTLAND, MAINE.

VELOCIPED-E-FORK.

SPECIFICATION forming part of Letters Patent No. 374,542, dated December 6, 1887.

Application filed May 20, 1887. Serial No. 238,832. (No model.)

To all whom it may concern:

Be it known that I, JOHN KNOUS, of the city and county of Hartford, in the State of Connecticut, have invented certain new and 5 useful Improvements in Velocipede-Forks, of which the following is a specification.

My improvements relate more particularly to those forks or portions of the frames of velocipedes which span and hold bearings for 10 wheels and are connected with fixed or non-rotating axles—such as the rear wheels of bicycles and the steering-wheels of tricycles—and I shall describe them as applied in the form in which I prefer to the rear fork of a bicycle, 15 though they will be obviously applicable with equal advantages elsewhere. Heretofore such forks have been constructed sometimes of three pieces of solid wrought metal, one piece forming the crown or arch and the other two pieces 20 forming the arms and axle-lugs, forged separately and welded to the other piece; and sometimes by stamping out of sheet metal or otherwise constructing a thin semi-tubular metal with two arms, one for each side of the wheel, 25 having at their lower ends additional pieces brazed on to form the axle-lugs; and sometimes of a single piece of tubular metal tapered and formed and cut out to make a homogeneous semi-tubular fork with axle-lugs formed there- 30 on, each arm being of a single thickness of thin and curved metal, and the lug formed thereon being of a single thickness and flattened; and sometimes of two pieces of sheet metal struck up in complementary form, each 35 forming one-half of a fork, the arms being also of semi-tubular form. In all these other forms of construction, however, there are certain disadvantages which it is desirable to overcome. In the solid forms there is either 40 too little rigidity or too great weight of metal, and in the semi-tubular forms, while lightness is obtained, there is too little rigidity in certain directions, especially a torsional weakness, allowing the wheel to be drawn out of 45 alignment by obstructions in the road, and there are in the best forms, besides, some difficulties of manufacture.

It is the object of my improvements to construct a fork which shall combine lightness 50 and grace with rigidity in every direction, and

particularly such rigidity as shall best retain the alignment or true of the wheel carried to its proper plane; and my improvement consists, first, in an improvement in the art of constructing a velocipede-fork with a solid 55 arch or crown, and with full tubular arms tapering and thickened toward the lug end with axle-lugs formed integrally therewith; and, secondly, in an improved fork containing the combination, with a crown-piece or arch, 60 of two full tubular arms, each of which is tapered and thickened and formed and constructed with an integral axle-lug, substantially as I will now proceed to describe.

In the accompanying drawings, Figure 1 65 shows a bicycle rear fork embodying my improvements in one form in elevation, and Fig. 2 shows the same in section. Figs. 3, 5, 7, and 11 show in elevation arm-pieces at different stages of construction; and Figs. 4, 6, 8, 10, 70 and 12 show sections of the same, respectively, on the broken lines of the other figures; and Fig. 13 shows in perspective a forging for the crown-piece or arch.

A A are the fork-arms; B B, the axle-lugs. 75 C is a crown-piece or arch, to which the arms are attached by brazing or otherwise, and D is a tenon for attachment to the perch or frame of the velocipede.

In constructing a fork according to my improved method I take for each fork two pieces of tube, as S, Figs. 3 and 4, of suitable length, and taper each by means of a pony-hammer to the form shown, as T, in Figs. 5 and 6, in such manner as to thicken the metallic shell at the 80 smaller end. I then, by means of dies or otherwise, for a bicycle rear fork, curve the tapered tube, as shown at U, Figs. 7 and 8. I then, by means of dies or formers, compress the hitherto tapered, thickened, and curved cylindrical tube into a flattened or nearly elliptical form, as shown at B and Figs. 9 and 10. I then form upon the smaller end a flattened lug, B, consisting in two thicknesses of the thickened tube compressed together integrally with 90 the fork-arm and strengthened by the gradual approach of the two sides of the elliptical fork end and without the addition of other metal. This lug is perforated, as shown, to receive the end of an axle or back wheel, B. I form, 100

by drop-forging, the arch or crown-piece C and tenon D in one piece, as shown in Fig. 13, the crown-piece having two short stubs, *c c*, to each of which the larger end of an arm, A, 5 may be brazed or otherwise secured.

I am aware that heretofore velocipede-forks have been made for front wheels of bicycles with a forged head for a crown-piece or arch with stubs, to which tubular fork-arms were 10 attached, and that forgings forming lugs for bearings have been attached by brazing or otherwise to the lower ends of such forks, and I therefore do not claim, broadly, a velocipede-fork having tubular arms.

15 I claim as new and of my invention—

1. The described improvement in the art of making a velocipede-fork, consisting in the tapering and thickening and forming of metallic tubes for the two arms and the axle-lugs homogeneous therewith, and the attachment 20 of these two arms to a crown-piece, essentially as set forth.

2. An improved velocipede-fork constructed with a crown-piece and two tubular arms, each arm thickened and tapered and formed to an 25 axle-lug at the end, essentially as set forth.

JNO. KNOUS.
